HYDRAULIC WORK HOLDING CLAMP

Vitas T. Thomas and Robert A. Lovdahl, Racine, Wis.,
assignors to Tomco, Inc., Racine, Wis., a corporation
of Wisconsin

Filed Apr. 8, 1968, Ser. No. 11,366

Term of patent 14 years

Int. Cl. D8—02

U.S. Cl. D55—1

FIG. 1 is a left front perspective view of the hydraulic work holding clamp.

FIG. 2 is a perspective view of the right side and back of the clamp.

FIG. 3 is an elevational view of the left side of the clamp.

FIG. 4 is a front elevational view of the clamp.

FIG. 5 is a top plan view of the clamp.

FIG. 6 is a bottom plan view of the clamp.

The dominant features of our design reside in the portions shown in full lines.

We claim:

The ornamental design for a hydraulic work holding clamp, as shown and described.
